UNITED STATES PATENT OFFICE.

JAMES C. GRIFFIN, OF ERIE, PENNSYLVANIA, ASSIGNOR TO GRIFFIN MANUFACTURING COMPANY, OF ERIE, PENNSYLVANIA, A CORPORATION OF PENNSYLVANIA.

CASEMENT AND DOOR LOCK.

1,113,331.

Specification of Letters Patent.

Patented Oct. 13, 1914.

Application filed June 24, 1914. Serial No. 847,003.

To all whom it may concern:

Be it known that I, JAMES C. GRIFFIN, a citizen of the United States, residing at Erie, in the county of Erie and State of Pennsylvania, have invented new and useful Improvements in Casement and Door Locks, of which the following is a specification.

This invention relates to casement and door locks and consists in certain improvements in the construction thereof as will be hereinafter fully described and pointed out in the claims.

The lock is particularly designed for doors such as garage doors where it is desired to lock the door in different position and particularly in an open position.

The invention is illustrated in the accompanying drawings as follows:

20 Figure 1 shows a plan view of a door with a part of a casing, the casing being partly broken away to better show construction. Fig. 2 an elevation of the same parts. Fig. 3 a detail of the locking plate in section on the line 3-3 in Fig. 1. Fig. 4 an end view of the hinge plate:

1 marks the door casing, 2 the door and 3 the hinges on which the door is mounted.

A locking rod 4 is pivotally mounted on a hinge plate 5. The hinge plate 5 consists of the perforated base 6 which may be secured to the door casing by means of screws, a downward bend 7 and the lip 8 with the return bend 9. The end of the locking rod 4 is placed between the return bend 9 and the lip 8 and secured by the pin 10 which forms the pivotal joint for the hinge between the rod 4 and the hinge plate 5.

A locking plate 11, preferably in the form of a loop with the extending feet 12 is secured to the door by means of screws 13 extending through the feet or flanges 12. The sides of the loop are provided with the slots 14 through which the rod 4 extends. The rod 4 is provided with the notches 15 which are so spaced and of such size as to engage the sides of the locking plate 11 at the bottoms of the slots 14. The rod 14 is preferably provided also with other notches as 16 so as to lock the door in various positions. As shown, the notches 16 will lock the door in a closed position and the notches 15 will lock the door in an open position.

55 It will be observed that when the door is

opened, the rod 4 will swing on the pin 10 and slide through the slot 14, the bottom of the rod resting on the bottom of the slot. When the notches 15 come into register with the sides of the locking plate they drop into engagement with the plate, thus locking the door in the position desired. It is preferable to place this locking rod at the upper end of the door so as to be out of the way and the casing forms a more desirable base for the rod in that the rod may be spaced from the hinge so as to more readily lock the door in an open position. In order to readily disengage the rod when thus locked I provide a trip lever 17. This is arranged within the sides of the loop 11 and pivotally mounted on the pin 18 extending between the sides of the loop. The outer end of this trip lever extends under the rod 4 and the inner end has a flexible cord or chain 19 depending from it terminating with a handle or ring 20 by which it may be readily operated.

It will be observed that the device may be used for a door opening on the opposite side by simply removing the pin and withdrawing the rod from the slot 14. The hinge plate is formed so that it will work equally well for a door opening either to the right or left and the locking plate is also adapted for opening either side.

What I claim as new is:

1. In a casement and door lock, the combination of a hinge plate; a locking rod pivotally mounted on the plate and having a locking notch in the bottom thereof; a locking plate adapted to pass into the notch in the rod as the rod slides over the plate; and a trip device carried by the locking plate and adapted to lift the rod to disengage it from the plate.

2. In a casement and door lock, the combination of a hinge plate; a locking rod pivotally mounted on the plate and having a locking notch in the bottom thereof; and a locking plate in the form of a loop with side flanges or feet extending therefrom, said loop having slots in the side walls thereof through which the locking rod extends, a side of the loop being adapted to enter the notch in the rod for locking the rod relatively to the plate.

3. In a casement and door lock, the combination of a hinge plate; a locking rod pivotally mounted on the plate and having a locking notch in the bottom thereof; a locking

plate in the form of a loop with side flanges or feet extending therefrom, said loop having slots in the side walls thereof through which the locking rod extends, a side of the loop being adapted to enter the notch in the rod for locking the rod relatively to the plate; and a trip lever pivotally mounted within the loop with one end under the rod and the opposite end being adapted to be operated to trip the rod.

4. In a casement and door lock, the combination of a hinge plate formed with a securing base and a hinge lip with a return bend; a locking rod having notches in the bottom thereof and pivotally secured between the lip and the return bend on the

hinge plate; a locking plate in the form of a loop having slots in the side walls thereof through which the locking rod passes, the sides of the loop being adapted to enter the notches in the rod to lock the rod in place; and a trip lever pivotally mounted between the sides of the loop and adapted to trip the locking rod.

In testimony whereof I have hereunto set my hand in the presence of two subscribing witnesses.

JAMES C. GRIFFIN.
